UNITED STATES PATENT OFFICE.

JOHN J. SCHILLINGER, OF NEW YORK, N. Y.

CABLE RAILWAY.

SPECIFICATION forming part of Letters Patent No. 337,623, dated March 9, 1886.

Application filed November 5, 1885. Serial No. 181,964. (No model.)

To all whom it may concern:

Be it known that I, JOHN J. SCHILLINGER, a citizen of the United States, residing at New York, in the county and State of New York, 5 have invented new and useful Improvements in Cable Railways, of which the following is a specification.

My invention relates to improvements in cable railways; and it consists in certain novel 10 features of construction, which are fully pointed out in the following specification and claims, and illustrated in the accompanying drawings, in which—

Figure 1 is a vertical transverse section in 15 the plane yy , Fig. 2, of a road-bed constructed according to my invention. Fig. 2 is a plan or top view of the same. Fig. 3 is an end view of the rail-supporting ties. Fig. 4 is a sectional view of the same.

20 Similar letters indicate corresponding parts.

In the drawings, the letter A designates the foundation of the railway-bed, which is constructed of cement, or other masonry suitable for the purpose, and through which extends longitudinally the usual conduit, B, in which are located the cable and cable-bearing pulleys, which latter are omitted in the drawings.

25 C are the rails, of any usual construction.

30 D D are the rail-supporting ties, and E E the crown-plates, which are connected with the supporting-ties, these plates forming the arch of the conduit. A narrow space is left between their upper ends to allow the introduction of the grip-bar.

35 Each rail-supporting tie D is constructed with a body or main portion of L-shaped cross-section, formed by a flange or base, d , and a deep rib, d' , while the end to which the crown-plate is secured terminates in a plate, d^2 , extending upwardly from the flange or base d , and having a curvature corresponding to the curvature of the crown-plates F. The crown-plates are secured to these plates d^2 by 40 bolts e , or by any other suitable means. The opposite end of each of the ties D is suitably formed to support the rail, which is secured thereto by bolts in the usual manner. In the example shown in the drawings this outer end

of the tie terminates in a trough-shaped support, d^3 , which rises a sufficient height above the base of the supporting-tie to bring the rail to the proper elevation, and to this trough or support the rail is secured by bolts e , or by other suitable means.

45 In constructing the road-bed the foundation A is built up, as shown, with the longitudinal conduit B, after which the ties are aligned at the proper distance apart, and the crown-plates E are secured in sections in their proper position 60 to the supporting-ties, with their lower ends abutting against the bed-foundation A. An upper layer or bed of cement, A', is then spread over the ties between the crown-plates E and the rails C, which firmly embeds the 65 ties in their proper position, the latter being facilitated by the T-shaped cross-section of the ties. The rails are then secured to the supports d^3 of the ties, the latter being open at the ends for this purpose.

70 The paving-stones F of the driveway are laid so as to abut against both outer ends of the supporting-ties, which assists in preventing lateral motion.

75 The upper surface of the cement bed may be divided in squares, or in other shapes, to improve the appearance of the track, and also to give a foot-hold to draft-horses when crossing the road.

Owing to the necessity of having a central 80 opening between the tracks in cable roads, continuous ties between the rails are impossible, and the object of this invention is to obtain a perfectly rigid road-bed, even without the use of longitudinal sleepers, which object 85 is accomplished by the use of the crown-plates and rail-ties constructed as described.

What I claim as new, and desire to secure by Letters Patent, is—

1. In a cable railway, the combination, with 90 the rail-supporting ties D D, of the crown-plates E E, connected with the rail-supporting ties, substantially as shown and described.

2. The combination, with the rail-supporting ties D D, having at their inner adjacent 95 ends the curved upwardly-projecting plates d , of the arched crown-plates E E, secured to said curved plates, substantially as described.

3. The road-bed for cable railways, consisting of foundation-bed A, the conduit B, the crown-plates E E, forming the arch of the conduit, the rails C, the ties D D, which are secured 5 to the crown-plates and the rails, and the upper road-bed, A', substantially as shown and described.

In testimony whereof I have hereunto set my hand and seal in the presence of two subscribing witnesses.

JOHN J. SCHILLINGER. [L. S.]
